UNITED STATES PATENT OFFICE.

JACK C. DODSON, OF MEXIA, TEXAS, ASSIGNOR TO MEXIA PLANING MILL COMPANY,
A COPARTNERSHIP COMPOSED OF L. J. INGRAM, JACK DODSON, AND JOHN W.
SWANN.

SUCKER-ROD GUIDE.

Application filed September 11, 1923. Serial No. 662,144.

To all whom it may concern:

Be it known that I, JACK C. DODSON, a citizen of the United States, residing at Mexia, in the county of Limestone and State of Texas, have invented certain new and useful Improvements in a Sucker-Rod Guide, of which the following is a specification.

This invention appertains to novel means for preventing wear on the sucker rod and on the well casing and the primary object of the invention is to provide a novel guide, which can be readily placed upon the sucker rod with a minimum amount of labor, and which will effectively form a guide for the sucker rod and prevent undue wear thereon and on the inner surface of the well casing.

Another prime object of the invention is to provide a guide for sucker rods embodying a two-part body and novel means for clamping the parts together on the sucker rod, the parts of the body having means for permitting the flow of fluid past the same and around the sucker rod.

A further prime object of the invention is to provide novel means for connecting the sections of the guide together, whereby accidental movement of these sections will be eliminated relative to one another, said connecting means permitting the quick placing and removing of the guide on the sucker rod.

A still further object of the invention is to provide an improved sucker rod guide of the above character, which will be durable and efficient in use, one that will be simple and easy to manufacture, and one which can be placed upon the market and incorporated with a sucker rod at a small cost.

With these and other objects in view, the invention consists in the novel construction, arrangement and formation of parts, as will be hereinafter more specifically described, claimed, and illustrated in the accompanying drawings, in which drawings:

Figure 1 is a slide elevation of the improved guide showing the same attached to a sucker rod.

Figure 2 is a detail section taken on the line 2-2 of Figure 1 illustrating the means employed for connecting the sections of the guide together.

Figure 3 is a horizontal section taken on the line 3-3 illustrating the cross sectional

configuration of the body portion of the 55 guide.

Figure 4 is a detail perspective view of one section of the improved guide.

Referring to the drawings in detail, wherein similar reference characters designate corresponding parts throughout the several views, the letter A generally indicates the improved guide, for a sucker rod B, which can be of any preferred type or character.

The guide A is preferably formed of wood, as this is the material which I found through actual experiment to be the best suited for the purpose intended, the use of iron and steel being discarded as providing too great a wearing surface against the sides of the well casing and sucker rod.

As clearly shown in the drawings the guide A comprises a cylindrical body 10 having an axial bore 11 therethrough for the reception of the sucker rod B. The terminals of the body 10 are provided with reduced sections 11, which are gradually tapered toward their outer ends. The body 10 is provided with longitudinally extending relatively wide grooves 13 which provide means for permitting the passage of the fluid between the guide and the well casing C, which is shown in dotted lines in Figure 1 of the drawings.

In order to facilitate the connection of the guide A with the sucker rod B, the body 10 is divided longitudinally to provide a pair of companion sections 15 and 16 which are provided with axial semicylindrical grooves 17 to provide the axial way 11'.

It is obvious that these sections can be readily placed around a sucker rod in view of the fact that one section can be placed on one side, and the other section on the other side.

In order to hold the sections 15 and 16 in clamping position on the sucker rod B, I employ sliding ferrules 18 and 19, which are adapted to slip over the tapered reduced terminals 11 of the body 10. In view of the fact that these terminals 11 are gradually tapered toward their outer ends, it is obvious that these rings or ferrules 18 and 19 will have a wedging effect thereon, to bring the sections into intimate contact with the sucker rod.

In order to prevent the slipping of these

ferrules 18 and 19 on the parts 11 I employ a pin 20, which can be extended through the ferrules and into said terminals 11.

What I claim as new is:

- 5 6. 1. A guide for sucker rods comprising a cylindrical body having a longitudinal bore intersecting the ends of the body, said body having reduced end portions with annular shoulders at the bases of the reduced end portions and clamping means embracing the respective reduced end portions of the body for drawing said end portions into engagement with a sucker rod, the major diameter of the body between its ends exceeding that of the clamping means, and said body being provided with external longitudinal channels having their opposite ends opening through the shoulders at the bases of the reduced end portions.
- 10 15. 2. A guide for sucker rods comprising a cylindrical body having a longitudinal bore intersecting its opposite ends, said body having reduced and tapered end portions with annular shoulders at the bases of the reduced end portions and clamping bands embracing the reduced tapered end portions of the body and capable of being driven inwardly thereon to clamp the body upon a sucker rod, the external diameter of the major portion of the body exceeding the external diameter of each clamping device, and the body of the guide being provided with external longitudinal channels having their opposite ends opening through the shoulders at the bases of the reduced end portions and outside of the clamping devices.
- 20 25. 3. A guide for sucker rods comprising a cylindrical body having a longitudinal bore intersecting opposite ends of the body, said body having reduced end portions with annular shoulders at the bases of the reduced end portions, said body being divided into longitudinal sections, and a clamping device embracing each reduced end portion for clamping the same upon a sucker rod, the
- 30 35. 4. A guide for sucker rods comprising a cylindrical body having reduced end portions with annular shoulders at the bases thereof, each reduced end portion being tapered, the body being provided with a longitudinal bore intersecting its opposite ends, said body being divided into longitudinal sections, clamping means embracing the reduced end portions and capable of being driven inwardly thereon to clamp the same upon a sucker rod, the external diameter of each clamping means being less than the external diameter of the body of the guide, and the body of the guide being provided with external longitudinal channels having their opposite ends opening through the shoulders.
- 40 45. 5. A guide for sucker rods comprising a cylindrical body having a longitudinal bore intersecting opposite ends of the body, said body having reduced end portions with annular shoulders at the bases of the reduced end portions, said body being divided into longitudinal sections, and a clamping device embracing each reduced end portion for clamping the same upon a sucker rod.
- 50 55. 6. A guide for sucker rods comprising a cylindrical body having reduced end portions with annular shoulders at the bases thereof, each reduced end portion being tapered, the body being provided with a longitudinal bore intersecting its opposite ends, said body being divided into longitudinal sections, clamping means embracing the reduced end portions and capable of being driven inwardly thereon to clamp the same upon a sucker rod, the external diameter of each clamping means being less than the external diameter of the body of the guide.

In testimony whereof I affix my signature.

JACK C. DODSON.
